UNITED STATES PATENT OFFICE.

CORA EDITH DUNAGAN, OF CLIFTON, ARIZONA.

COMBINED MOP AND SCRAPER.

1,282,780.

Specification of Letters Patent. Patented Oct. 29, 1918.

Application filed June 14, 1918. Serial No. 240,063.

To all whom it may concern:

Be it known that I, CORA E. DUNAGAN, a citizen of the United States, residing at Clifton, in the county of Greenlee and State 5 of Arizona, have invented new and useful Improvements in Combined Mops and Scrapers, of which the following is a specification.

This invention relates to new and useful 10 improvements in a combined mop and scraper and the principal object of the invention is to provide means for moving the scraper into and out of operative position.

Another object of the invention is to provide 15 a device of this character which is simple and durable in construction, reliable and efficient in operation and one which can be manufactured and placed upon the market at a minimum cost.

20 The invention also consists in certain other features of construction and in the combination and arrangement of the several parts, to be hereinafter fully described, illustrated in the accompanying drawings and 25 specifically pointed out in the appended claims.

In describing my invention in detail, reference will be had to the accompanying 30 drawings wherein like characters denote like or corresponding parts throughout the several views, and in which:—

Figure 1 is a front view of the device.

Fig. 2 is a side view.

35 Fig. 3 is a cross section showing the means for holding the scraper in operative position.

As shown in these views the handle of the mop is shown at 1 and the mop carrying head at 2. 3 is the yoke for holding the 40 mop to the head and connected with the operating member 4 which has one end connected with the coil spring 5 whereby mops of varying thicknesses may be secured between the yoke and the head.

45 As my invention relates to the scraper the parts composing the mop will not be described further. The scraper consists of a handle part 6 and the scraping blade 7 connected with the end of said handle and having its free end slightly curved as shown. The handle 6 is connected with the handle 1 of the mop by means of the rings 8 formed

of metal or the like and each is provided with a pair of ears 9. Each of these ears is provided with an opening through which 55 the handle 6 passes and said openings are so disposed that the handle 6 is spaced from, but parallel with the handle 1 of the mop.

One of the ears, preferably the upper one is provided with a slot 10 in its outermost 60 edge which communicates with the opening and the handle 6 is provided with a transverse pin 11 which when the blade is in operative position will pass through the slot and engage the lower face of the ear to 65 hold said blade in operative position or with said blade projecting beyond the head of the mop. The pin is so located that when the same is turned out of alignment with the slot said blade will be parallel with the 70 head of the mop and thus be in proper position for scraping the floor. The lower part of the handle 6 is provided with a transverse pin 12 and a coil spring 13 surrounds said handle and has its ends bearing against 75 said pin and one of said ears.

It will thus be seen that when the pin 6 is out of engagement with the bottom face of the slotted ear the coil spring 13 will throw the scraping blade above the head of 80 the mop and into inoperative position.

When it is desired to scrape the floor it is simply necessary to move the handle 6 downwardly until the pin 11 passes through the slot 10 and then by turning the handle 85 to move the blade into a position parallel with the head said pin will be turned to engage the bottom face of the ear and will thus hold the scraper blade in extended position. This will leave both hands of the 90 operator free to handle the device.

It is thought from the foregoing description that the advantages and novel features of my invention will be readily apparent.

I desire it to be understood that I may 95 make such changes in the construction and in the combination and arrangement of the several parts, provided that such changes fall within the scope of the appended claims.

What is claimed is:—

1. An attachment for mops comprising a handle slidingly secured to the mop handle, a scraper blade secured to the first mentioned handle, means for holding the blade

beyond the end of the mop and spring means for holding the scraper in retracted position.

2. A device of the class described comprising a rod, a number of rings carried thereby, each ring having a pair of ears thereon provided with openings and one of said ears being slotted, a scraper having a

handle passing through said openings, a transverse pin on said handle for engaging 10 with the slotted ear to hold the scraper in extended position and spring means for normally holding said scraper in inoperative position.

In testimony whereof I affix my signature. 15
CORA EDITH DUNAGAN.
